United States Patent Office

Des. 204,474
Patented Apr. 19, 1966

204,474

CUP HOLDER

Bertrand N. Trombley, Bloomfield Hills, Mich., assignor to The Dow Chemical Company, Midland, Mich., a corporation of Delaware

Filed Oct. 15, 1964, Ser. No. 82,183

Term of patent 14 years

(Cl. D44—10)

Fig. 2

Fig. 1

Fig. 4

Fig. 5

The dominant features of my design reside in the portions shown in full lines.

I claim:

The ornamental design for a cup holder, substantially as shown and described.
